CLAIM

I claim the ornamental design for a handguard for a pump action shotgun, as shown and described.

DESCRIPTION

FIG. 1 is a front view of the handguard for a pump action shotgun, showing my new design;

FIG. 2 is a left side view thereof, the right side being a mirror image;

FIG. 3 is a top view thereof;

FIG. 4 is a bottom view thereof;

FIG. 5 is a rear view thereof;

FIG. 6 is a rear perspective view thereof; and,

FIG. 7 is a front perspective view thereof.
